UNITED STATES PATENT OFFICE.

JOHN NEUMANN, OF CHICAGO, ILLINOIS.

BUILDING BLOCK OR BRICK.

Application filed February 8, 1922. Serial No. 534,893.

To all whom it may concern:

Be it known that I, JOHN NEUMANN, a citizen of the United States, residing at Chicago, in the county of Cook and State 5 of Illinois, have invented certain new and useful Improvements in Building Blocks or Bricks, of which the following is a description.

My invention relates to improvements in 10 bricks or blocks, and more particularly to blocks that may be employed for building purposes or the like, including furnace and fire arch constructions.

One of the objects of my invention is to 15 provide an interlocking block so constructed as to cause all of the blocks in a wall to interlock with each other independently of the bonding material used, and further, to provide interlocking means that act as 20 guides in aligning or laying up the wall so as to permit inexperienced workmen to easily and accurately set the blocks in walls of all kinds.

A further object of the invention is to 25 provide an interlocking block so formed as to permit it to be laid so as to interlock with other blocks in adjacent courses and which may be laid transversely of other courses to cross-bond the same and interlock 30 with the blocks in the cross-bonded courses.

Another object of my invention is to provide blocks as above described which will be hollow, making them extremely light in 5 weight without sacrificing strength, and also forming individual heat-insulating, dead-air spaces in each block when they are built into a wall.

Many other objects and advantages of the 40 construction herein shown and described will be obvious to those skilled in the art from the disclosures herein given.

To this end my invention consists in the 45 novel construction, arrangement and combination of parts herein shown and described, and more particularly pointed out in the claims.

In the drawings, wherein like reference 50 characters indicate like or corresponding parts,

Fig. 1 is a top plan view of a wall embodying my invention;

Fig. 2 is a side elevation thereof;

Fig. 3 is a section taken substantially on the line 3-3 of Fig. 1;

Fig. 4 is a section taken substantially on the line 4-4 of Fig. 2;

Fig. 5 is a perspective of one form of block as seen from above;

Fig. 6 is a perspective of the same block as seen from below;

Fig. 7 is a perspective of a modified form of block as seen from below, and

Fig. 8 is a perspective of the block shown in Fig. 7 as seen from above.

The preferred form of block, shown in 65 Figs. 5 and 6 is of substantially rectangular form, having a top wall 1, side walls 3 and 4 and end walls 5 and 6, the edge 2 of the side and end walls forming the bottom of the block, but it is to be understood that the 70 invention applies equally to blocks of other form or shape for which it may be rendered adaptable.

The interior of the block is hollowed out, 75 to form an opening as at 7, so that the walls of the block are comparatively thin. Along the inner meeting edges of the top wall of the block, with the walls perpendicular thereto, the block is preferably increased in thickness, as at 9, so as to strengthen the 80 block along these edges.

At the upper face 1 of the block there are provided projections or lugs 8, made of any suitable form, but in the present instance are of polygonal outline and preferably, 85 square. It will be noted that the projections are rounded off toward their upper or outer ends so that their bases are of greater area than their inner or lower ends. The 90 projections 8 are disposed midway between the side edges of the block and midway between the ends of squares equal on all sides to the width of the block, but which are separated from each other at the middle of the block at a distance equal to double the 95 thickness of the side walls of the block plus the width of the mortar joint employed. This is particularly shown in Fig. 1.

The width of the rectangular opening 7 is slightly greater than the length of the 100 sides of the projections 8, and the length of the opening 7 is slightly greater than the distance between the sides of the projections adjacent the ends of the blocks, so that when the blocks are superimposed in 105 wall formation with the mortar, the bases of the projections will so closely fit the recess 7 as to tend to nest and prevent relative lateral or longitudinal movement of the blocks. Thus, when the layer of mortar is interposed 110 between the blocks there will be a very small peripheral space around each projection and

around the peripheral walls thereof and the opposed walls of the recess 7 to receive some of the mortar. It will be noted that the edges of the projections 8 are rounded or 5 tapered off, as at 10, so as to facilitate the assembly of the blocks.

The blocks thus formed will interlock with each other, whether laid in staggered relation to each other or otherwise in the 10 courses, or transversely to each other, as in cross-bonding corner construction, as will be obvious. Thus, a wall constructed of these blocks will be exceedingly strong and because of the fact that the projections and 15 recesses will act as guides for properly relatively positioning the blocks in the wall, such walls may be built by inexperienced workmen at a low cost and yet produce a properly finished and durable construction.

20 In laying it is not necessary for the workmen to spread the mortar on the blocks with a trowel, but the open end of the blocks may be dipped in the mortar and then laid the same as if the mortar were hand applied.

25 In the modified form shown in Figs. 7 and 8, the block is hollowed out throughout the interior thereof so as to provide relatively thin walls, except that in this case the end wall 6' is open instead of the bottom 30 wall. The square projections 8' are of less length than the inner length of the opening 7 between the parallel walls 3', 4', and consequently the recesses 11 formed through the lower wall 2' must be of substantially the 35 same size and shape as the projections 8', so that when the blocks are superimposed on each other in courses, the projections 8' of the lower block will be received in the recesses 11 of the upper block whether the 40 blocks are laid in the same direction in adjacent courses, or when laid transversely of each other as when cross-bonding.

45 It will be noted that when the blocks are laid in wall formation that the hollowed interiors 7 form individual and discontinuous insulating or dead-air spaces, which is especially desirable in practically every form of wall construction, as for instance in boiler settings, fire brick arches and the like.

50 Having thus described my invention, it is obvious that various immaterial modifications may be made in the same without departing from the spirit of my invention;

hence I do not wish to be understood as limiting myself to the exact form, construction, arrangement and combination of parts herein shown and described or uses mentioned.

What I claim as new and desire to secure by Letters Patent is:

1. A hollow block of the kind described having one side open the entire area of said side except at the bounding edges of the block, and a polygonal lug projecting from one face, of a size to be received in a recess provided in a mating block when said first-mentioned block is arranged either longitudinally or transversely of the mating block.

2. A block of the kind described having top, bottom, side and end walls, and provided with a chamber in its interior, said bottom wall provided with a rectangular opening therethrough communicating with said chamber, and a pair of spaced square lugs on said top wall, either or both of which are adapted to non-rotatably enter said rectangular opening of a mating block, so that said blocks may be superimposed either longitudinally or transversely of one another.

3. A wall composed of a series of courses of blocks laid in staggered relation to each other, each of said blocks being hollow throughout its interior so that the bounding faces form a shell and provided with at least one projection on one face disposed midway between one end and the middle and midway the side edges thereof, and in its opposite face with a similarly positioned recess adapted to receive the projections of a block in another course, said recess and projections constituting guides for accurately determining the relative positions of the blocks in each course and constituting means for preventing splitting of the wall in the mortar joints, said interlocking means comprising means whereby corner blocks may be laid transversely to each other and interlocked.

In testimony whereof, I have hereunto signed my name in the presence of two subscribing witnesses.

JOHN NEUMANN.
